UNITED STATES PATENT OFFICE.

IRWIN A. HILL, OF FAIRBURY, NEBRASKA.

ELECTRIC CALL SYSTEM FOR HOTELS.

1,411,497.

Specification of Letters Patent. Patented Apr. 4, 1922.

Application filed August 9, 1920. Serial No. 402,225.

To all whom it may concern:

Be it known that I, IRWIN A. HILL, a citizen of the United States, residing at Fairbury, in the county of Jefferson and State of Nebraska, have invented certain new and useful Improvements in Electric Call Systems for Hotels; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

The object of this invention is to provide a novel electrically-operated call system for hotels, apartment houses, etc.

With this object in view, the invention resides in the novel construction, combination and arrangement of parts as will be hereinafter fully described in the specification, pointed out in the claim and illustrated in the accompanying drawings.

The drawings form a part of this specification, and like reference characters designate corresponding parts throughout the several views. Briefly described:

Figure 1 is a diagrammatic view of my electrically-operated call system, showing the application thereof to a signal in one room of a hotel, or the like;

Figure 2 is a similar view of the application of my system to a plurality of signals in a plurality of rooms;

Figure 3 is a view, in front elevation, of a portion of the mechanism;

Figure 4 is a view, in side elevation, of the part shown in Figure 3;

Figure 5 is a view, in front elevation, of a disk carrying a plurality of contacts, and forming part of the system;

Figure 6 is a fragmentary sectional-detail view of said disk, and

Figure 7 is a collective detail view of sections of the switch box.

Referring now in detail to the drawings:

1 and 2 designate the main wires of an electric circuit. 6 designates an entrance switch, and 7 designates a meter. The conductor wires 1 and 2, leading from the meter, may pass to the lighting system of the hotel. Wires 3 and 4 lead from the conductors 1 and 2, respectively, and pass to a transformer 8. The wire 4, leading from the transformer, passes, as shown, to an

audible signal, such as a bell 9, supposed to be in the room of a building, such as a hotel, or the like. The other wire 3, passing from the transformer, leads to a copper contact plate 10, preferably formed as a disk concentrically disposed in a disk 11, suitably supported in any desired manner.

An annular series of contacts 12 are carried by said disk 11, toward the margin thereof, and are suitably insulated therefrom, as by means of an insulation annulus 13 inserted in said disk.

The wire 3, leading from the transformer 8, is connected with the contact plate 10.

A rotatable switch member 14 is carried by the disk 11, the axis of rotation of said switch member being the center of said disk. Said switch member 14 carries, toward its ends, contacts 15 and 16, the latter contact bearing upon the contact plate 10. Said switch member 14 is mounted in any suitable manner upon the arbor 17 of the hour hand of a clock 18, and is automatically controlled by the rotation of said arbor. The other contact 15, carried by the switch member 14, describes a path of movement in line with the contacts 12, carried by the disk 11, and successively engages said contacts in the rotation of said switch member. Said contacts 12 are equi-distantly spaced on the disk 11; and in this instance I have shown forty-eight of these contacts, said contacts being thus spaced, in terms of time of travel of the clock hour hand, fifteen minutes apart.

19 designates a switch box, supposed to be located within convenient reach of the hotel clerk, said box preferably comprising a flat bottom 20, a right-angled back wall 21, end walls 22 and a curvilinear front wall 23, provided with a plurality of, preferably, equi-distantly spaced slots 24, in this instance, four being shown. Adjacent each slot 24 is disposed an arcuate insulation strip 25, carrying a plurality of equi-distantly spaced contacts 26, twelve of such contacts being shown in connection with each strip 25, the aggregate of the contacts on all four of said strips being thus forty-eight, corresponding in number to those of the contacts 12 of the disk 11. Movable in each slot 24 is a movable switch 27 pivotally secured at one end thereof, as shown at 28, to the switch box 19 near the bottom thereof, and being properly insulated from said box. The several switches 27 are electrically con-

ected by the wire 5 which leads to the bell 9. Each of said switches 27 is normally disposed flatly against the rear wall 21 of the box, and the exteriorly projecting end 5 of each switch is provided with a knob 29 for the convenient manipulation of the switch. In such normal position the switch is out of engagement with the contacts 26 carried by the adjacent insulation strip 25, 10 but it will be noted that if any one of said switches 27 is moved from the vertical position thereof, toward a horizontal position, it engages successively said contacts 26.

The exterior surface of the curved front 15 wall 23 of the switch box may bear suitable indicia to identify the switch 27; and by inspecting Figure 1, it will be seen that, preferably, the inscriptions or legends "1 hr" 20 "1/4" "1/2" and "3/4" are used to designate the respective switches. The exterior surface of 25 the curved wall 23 of said box also bears indicia identifying the twelve contacts 26, said contacts being progressively identified by the reference numerals 1 to 12, as shown in Figure 1. The contacts 26 of each of the four series are spaced, in terms of time, one hour apart.

Wires 28 lead from the contacts 12 to a terminal board 29 and thence to the switch 30 box 19, where they are connected with the contacts 26. The wires 28, leading from those contacts 12 corresponding to the hours on the dial of the clock 18, are connected to the corresponding contacts 26 cooperating 35 with the switch 27 identified in Figure 1 by the legend "1 hr", this switch 27 being thus the hour switch. Those wires 28 which are identified in Figure 3 by the fraction "1/4", (each of said wires leading from a contact which corresponds to the division number on the clock dial, representing the travel of the hour hand through a time interval of fifteen minutes after any given hour), lead to the contacts 28 cooperating with the 40 switch 27 immediately succeeding the hour switch and identified by the fraction "1/4" on the switch box 19, shown in Figure 1. In like manner the wires 28, identified by the fractions "1/2" and "3/4" in Figure 3, lead 45 respectively to the contacts 26, cooperating with the levers 27 identified by the fractions "1/2" and "3/4" on the switch box 19, shown in Figure 1.

In operation, it will be seen that if a 50 guest in the room of the hotel, in which the bell 9 is located, desires to be called at,

say, six o'clock in the morning, the clerk of the hotel pulls the switch 27, identified by the legend "1 hr" in Figure 1, downward, until it is in line with the contact 26, identified by the numeral 6 in the column of numerals appearing in Figure 1 on the switch box 19. Consequently, when the hour hand of the clock 18 points to "6" on the clock dial, the hour hand arbor will have 65 been rotated to bring the contact 15 of the switch 14 into engagement with the contact on the disk 11, from which leads the wire 28, identified in Figure 3 by the numeral 6. The current will then flow through the disk 70 10, along the switch 14, through the engaged contacts 15 and 12, and along the wire 28 connected with the contact 26, with which said switch lever is engaged, as before stated, and thence through said switch 27 to the 75 conductor 5 leading to the bell 9, thus completing the circuit.

If the hotel guest desires to be called at, say, fifteen minutes after seven o'clock in the morning, the switch 27, identified by the fraction "1/4", appearing on the switch box 80 19 shown in Figure 1, is pulled downward until it engages with the contact 26, identified by the reference numeral 7 on the switch box 19, shown in Figure 1.

Figure 2 merely shows the wiring leading from a plurality of bells 9 disposed in a plurality of rooms of a hotel, or the like, a plurality of switch boxes 19 being, of course, used, in this instance, three rooms of a hotel 90 being shown and three switch boxes 19, one switch box being used for the corresponding room of the hotel.

What I claim to be new is:

The combination of a time switch, a selective switch for said time switch comprising co-axial switch members, an index, the co-axial members provided with contacts, the contacts connected with the time switch and arranged so that one of the co-axial 95 members will make a circuit through the time switch on even hours and another of the co-axial members will make a circuit through the time switch at fractions of an hour, the co-axial members with their contacts and the index relatively arranged so that the fraction of an hour contact is aligned on the index with the preceding full hour contact.

In testimony whereof I hereunto affix my 110 signature.

IRWIN A. HILL.
